COMBINATION BROILER AND FRIER

Robert D. Budlong, Skokie, Ill., assignor to Cory Corporation, Chicago, Ill., a corporation of Delaware

Application January 19, 1953, Serial No. 23,193

Term of patent 7 years

(Cl. D81—10)

To all whom it may concern:

Be it known that I, Robert D. Budlong, a citizen of the United States, residing at Skokie, in the county of Cook, and State of Illinois, have invented a new, original, and ornamental Design for a Combination Broiler and Fryer, of which the following is a specification, reference being had to the accompanying drawings, forming part hereof.

In the drawings:

Fig. 1 is a perspective view, in non-use position, of a combination broiler and fryer embodying my new design.

Fig. 2 is a front elevational view of the combination broiler and fryer in the same position as Fig. 1.

Fig. 3 is a rear elevational view of the combination broiler and fryer.

Fig. 4 is a top plan view of the combination broiler and fryer positioned for use.

Fig. 5 is an end elevational view of the combination broiler and fryer positioned for use.

I claim:

The ornamental design for a combination broiler and fryer, as shown.

ROBERT D. BUDLONG.
